The ornamental design for distance measuring unit for an automatic focusing camera, as shown and described.

DESCRIPTION

FIG. 1 is a perspective view of the top front and one side of a distance measuring unit for an automatic focusing camera showing our new design;

FIG. 2 is a front elevational view thereof;

FIG. 3 is a top plan view thereof;

FIG. 4 is a side elevational view of said one side;

FIG. 5 is a side elevational view of the opposite side thereof;

FIG. 6 is a rear elevational view thereof; and,

FIG. 7 is a bottom plan view thereof.

*FIG. 1**FIG. 2*FIG. 3

FIG. 4

FIG. 5

*FIG. 6**FIG. 7*
